UNITED STATES PATENT OFFICE.

ARTHUR E. BERGQUIST, OF LINDSTROM, MINNESOTA.

FINGERPRINT DETECTOR AND DEVELOPER.

Application filed December 26, 1923. Serial No. 682,817.

To all whom it may concern:

Be it known that I, ARTHUR E. BERGQUIST, a citizen of the United States, residing at Lindstrom, in the county of Chisago and State of Minnesota, have invented new and useful Improvements in Fingerprint Detectors and Developers, of which the following is a specification.

My present invention has to do with the identification of individuals by finger prints, and it has for its object the provision of a device through the medium of which finger prints can be detected and developed in an expeditious and thorough manner.

15 To the attainment of the foregoing, the invention consists in the improvement as hereinafter described and definitely claimed.

In the accompanying drawings, forming part of this specification:—

20 Figure 1 is a view illustrating the face of the device constituting the preferred embodiment of my invention.

Figure 2 is a side elevation of the same.

Figure 3 is a longitudinal vertical section 25 of the device taken in the plane indicated by the line 3—3 of Figure 1.

Figure 4 is a view similar to Figure 3 but showing a modification hereinafter explicitly referred to.

30 Figure 5 is a detail view hereinafter explicitly referred to.

Similar numerals designate corresponding parts in Figures 1 to 4 to which reference will first be made.

35 Among other elements the preferred embodiment of my invention comprises a casing 1, tapered toward one end and having a comparatively large and rounded opposite end 2 and also having an opening 3 in one side and extending through the major portion of the length thereof. The said casing 1 is in the nature of a receptacle, and in it are arranged two transverse shafts 4 and 5, the shaft 4 being equipped with pulleys 6,

40 and the shaft 5 being equipped with comparatively large pulleys 7. On the said pulleys 6 and 7 are flexible belts 8 arranged in parallelism, which belts because of the differences in size between the pulleys 6 and 50 the pulleys 7 are arranged with their outer stretches opposite and adjacent the opening 3 in the casing. The inner stretches of the belts 8 are as clearly shown arranged adjacent to the bottom wall 9 of the casing.

55 Carried by the belts and extending trans-

versely between the same are slats 10 on which are lips 11. Fixed to the shaft 5 and arranged exteriorly of the casing 1 is a crank 12 through the medium of which said shaft can be conveniently rotated for the movement of the belts 8 and the slats 10 thereon. At 13 in the casing is an auxiliary transverse shaft on which is an arm 14 fixed to the shaft 13 and carrying adjacent to its free end a comparatively short transverse shaft 15 on which are rollers 16 adapted to engage the inner sides of the outer stretches of the belts 8 under conditions hereinafter described. A coiled spring 17 surrounds the auxiliary shaft 13 and is connected at one end thereto and at its opposite end to the casing 1. This spring 17 is adapted when the arm 14 is released to press and yieldingly hold the roller 16 against the outer stretches of the belts 8.

55 As shown in Figures 1 to 3, the rollers 16 are held out of operation by a transverse removable rod 18 which by resting in the side walls of the casing 1 and over the arm 14 serves to effectively hold the roller 16 in spaced relation to the outer stretches of the belts 8.

Under a special condition hereinafter referred to, the rod 18 is removed as shown in Figures 4 and 5 so as to enable the spring 17 to yieldingly press the rollers 16 against the inner sides of the belts 8.

60 In the practical use of my novel finger print detector and developer as illustrated in Figures 1 to 4, the receptacle formed by the casing 1 is supplied with a sufficient quantity of chemicals adapted to adhere to the lines of a finger print and hence bring the said lines out for identification purposes.

The face of the device is then placed over the finger print and the crank 12 is turned whereupon the chemicals will be picked up by the cross slats 10 as said slats pass over the large pulleys, and thereafter the chemicals will be thrown by the cross slats against

65 the surface bearing the finger print with the result indicated. Manifestly some of the chemicals will adhere to the lines of the finger print and the excess chemicals will fall and be caught in the receptacle afforded by the casing.

70 From this it follows that finger prints that are so faint or obscure that they can hardly be seen with the naked eye can be developed or made prominent through the medium of my novel device, and

105

110

this much more safely than can be accomplished with a brush, a brush being objectionable because of the liability of some of the lines being obliterated by the friction of the brush against the surface.

When it is necessary to use the device in an overhead position, as when a finger print occurs on a ceiling, the rod 18 is removed so as to enable the spring 17 to press the roller 16 in yielding manner against the inner sides of the outer stretches of the belts 8. Then the face of the casing—i. e., the side thereof in which the opening 3 is provided, is held against the ceiling, and the crank 12 is rotated, when it will be seen that the cross rods 19 extending between the large pulleys 7 adjacent the peripheries thereof will serve by engaging the short portion of the arm or lever 14 to suddenly throw the roller 16 against the outer stretches of the belts 8 at intervals. In other words the tappet rods 19 put the spring 17 under tension so that as each tappet rod 18 passes out of engagement with the arm or lever 14, the spring 17 will quickly impel the rollers 16 against the outer stretches of the belt. In consequence of this at intervals portions of chemicals on the slats 10 will be thrown against the surface bearing the finger print so that the lines of the said print will be made perfectly clear. Manifestly the rod 18 is adapted to be expeditiously and easily removed and as readily replaced in the casing 1 according to the manner in which the device is to be employed. It will be understood from the foregoing that the device may be made in different sizes without in any way affecting my invention, and it will be apparent from the foregoing that the device is simple and inexpensive in construction, is highly efficient in operation and is well adapted to withstand proper usage for an indefinite period of time.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be

made such as fall within the scope of my invention as defined in my appended claims.

Having described my invention, what I claim and desire to secure by Letters-Patent, is:—

1. A device for developing or making more prominent finger prints, comprising a casing adapted to contain a substance calculated to adhere to the lines of a finger print and render the same more readable, said casing having an opening for the passage therefrom of the said substance, and movable, manually-operable means in the casing for bringing about the movement of said substance from the interior of the casing to the print to be developed or made more prominent, the said casing being tapered toward one end and being provided with shafts and pulleys thereon, one of the pulleys being comparatively large, and the said pulleys being associated with a belt, and means on the belt at intervals in the length thereof to take up chemicals and means for cooperating with the belt to discharge chemicals through the opening in the casing. 60

2. A device for developing or making more prominent finger prints, comprising a casing adapted to contain a substance calculated to adhere to the lines of a finger print and render the same more readable, said casing having an opening for the passage therefrom of the said substance, and movable, manually-operable means in the casing for bringing about the movement of said substance from the interior of the casing to the print to be developed or made more prominent, the said casing being tapered toward one end and being provided with shafts and pulleys thereon, one of the pulleys being comparatively large, and the said pulleys being associated with a belt, and means on the belt at intervals in the length thereof to take up chemicals and discharge the same through the opening in the casing, and the belt being associated with spring pressed tappet means to strike the inner side of the belt at intervals, and the said tappet means being associated, in turn, with means on one of the pulleys for putting the spring under tension and suddenly releasing the same. 95

In testimony whereof I affix my signature.

ARTHUR E. BERGQUIST.
